UNITED STATES PATENT OFFICE.

JOHN GLENDON, OF MALDEN, MASSACHUSETTS.

FOLDING MACHINE.

1,405,776.

Specification of Letters Patent.

Patented Feb. 7, 1922.

Application filed September 3, 1920. Serial No. 407,975.

To all whom it may concern:

Be it known that I, JOHN GLENDON, a citizen of the United States, residing at Malden, in the county of Middlesex and State of Massachusetts, have invented a new and useful Improvement in Folding Machines, of which the following is a specification, reference being had therein to the accompanying drawings.

10 My invention relates to folding machines and more particularly to a folding machine provided with means for impressing a design upon the outer surface of the material being folded at or near the folded edge simultaneously with the folding operation.

At the present time it is customary after the folding of the edges of rubber parts used in the manufacture of rubber shoes, to run a hand roller having a pinking surface over 20 the rubber parts near the edges in order to impress a lineal design either in imitation of stitching or of a decorative character. This being a hand process in addition to the folding operation, is necessarily slow and consumes time, thereby increasing the cost of the 25 parts.

The main object of my invention is the provision of a folding machine provided with means for impressing a design adjacent to 30 the edges of the folded material in order that the folding and the impressing operations may be carried out simultaneously in one operation.

Other objects of the invention will be more 35 specifically set forth hereinafter.

In the accompanying drawings illustrating one embodiment of my invention, Figure 1 is a front end elevation of a folding machine, looking from left to right with respect to the 40 station of the machine operator, showing the preferred form of invention; Fig. 2 is a side elevation of the front end of the machine as viewed from the station of the operator; Fig. 3 is a vertical sectional view on line 3—3 in Fig. 1, looking from left to right; Fig. 4 is a cross-sectional view on line 4—4 in Fig. 1; and Fig. 5 is a detail view of the pressing surface of the hammer or pressing means.

50 In the drawings I have shown my invention as applied to a folding machine of the general construction and mode of operation shown and described in United States Letters Patent No. 1,294,919, issued to William F.

Lautenschlager, February 18, 1919. Only 55 such parts of the machine are shown as are necessary to illustrate my invention and reference may be made to said patent for a full description of the parts not shown. My invention may be applied to various other forms 60 of folding machines by slight changes of construction which would be apparent to one skilled in the art, and therefore, it is not to be limited to the particular embodiment herein shown and described.

65 Referring to the drawings, in which is shown the forward ends of two forwardly extending arms, 10 designates the upper arm and 11 the lower arm, both of which are carried by a frame or standard, not shown. A 70 work-plate 13, upon which the material is supported, is mounted on the upper face of the lower arm.

The folding instrumentalities mounted on 75 the ends of the two arms 10 and 11 comprise a gauge 14 against which the work is held during its passage through the machine, a fold-turner or plow 15 for turning over the edge of the work to be folded, a feed-foot 16 operating in conjunction with an idler 80 feed-roll 17, for feeding the work forwardly in a step-by-step manner, a presser-foot 18 for holding the work between the feeding movements and a fold-presser or hammer 19 for pressing the turned over edge down 85 upon the body-portion of the material and completing the fold. The gauge 14 and plow 15 are of the same form and have the same 90 functions as those members shown in the Lautenschlager patent, but the remainder of the folding instrumentalities have been changed or modified in construction and other elements added in order to accomplish the additional result desired.

95 In the application of my invention to the Lautenschlager machine, I utilize the feed-roll 17 for impressing the design on the material by constructing it in two parts or washers, as shown in detail in Figure 4, and interposing between the two parts a pinking disk 25 having its periphery formed to impress the desired design. The pinking disk shown is provided with saw teeth on its periphery in order to secure imitation stitching, but it may be so formed as to produce other designs of a lineal character. The parts of the roll 17 with the pinking disk 25 may be held in assembled condition by any suitable means,

such as screws 26. The roll 17 is loosely mounted on a headed stud 27 screwed into the end of the lower arm 11, a washer 28 being interposed between the roll and the head 5 of the stud.

For pressing the material down upon the periphery of the pinking disk 25 as it is fed through the machine, in order to impress the design, any suitable means may be provided 10 and one such means is shown comprising a plunger 30 which is arranged in relation to the feeding means and operated in conjunction therewith in the following manner.

The feed-foot 16, having its lower face 15 provided with teeth for gripping the material in feeding, is an integral part of a hollow feed-bar 32 slidably mounted in a feed-housing 33 carried by a feed-shaft 34 which has a rocking movement in order to accomplish the feeding. The up and down movement of the feed-bar is imparted from a rock-shaft 36 by the following means. A split collar 37 carrying a short arm 38 is fastened on the end of the rock-shaft 36 and 25 the free end of the arm 38 is connected by a headed pin 39 to a link 40 having its upper end in the form of a yoke, within which slides a square block 42 carried by a split collar 43 fastened around the top of the feed-bar 32 by a screw 44. The block is held in position by a screw 45. The rocking of the shaft 36, through the medium of the arm 38, link 40 and collar 43 causes the feed-bar 32 to be reciprocated within the housing 33 to 30 drop the feed-foot onto the material at the beginning of the feeding movement and to raise it from the material at the end of the feeding movement. A spring 46 attached at one end to a hooked pin 48 set in the housing 35 33 and at the other end to a similar pin 49 in the split collar 43, is under tension at all times and tends to maintain the feed-bar 32 in a lowermost position yet permitting it to yield when the material increases in thickness. The foregoing construction is set forth 40 in detail in said Lautenschlager patent.

The plunger 30 is an integral part of a plunger-bar 50 slidably mounted in the hollow feed-bar 32. Above the plunger-bar 50 50 is arranged a hood 51 which is fastened to the yoke portion of the link 40 by a screw 52, the lower end of the body of the hood being curved inwardly and recessed to engage the link 40. The hood is thereby held 55 stiff when any upward pressure is brought to bear against it. The upper end of the plunger-bar 50 is bored and threaded to receive a flat-headed screw 54 which passes loosely through a hole in the hood 51. Between the hood and plunger-bar is a coiled 60 spring 55 under pressure, which tends to push the plunger-bar downwardly and to keep the flat head of the screw 54 in engagement with the top surface of the hood. The 65 downward movement of the plunger-bar in

relation to the feed-bar is limited by the shoulder 56 formed on the inside of the feed-bar when engaged by a similar shoulder 57 on the plunger-bar. In the operation of these parts the plunger 30 travels with the 70 feed-foot 16 until they both strike the material at the beginning of the feeding movement when the plunger presses the material downwardly upon the pinking disk 25 and the feed-foot presses the material against the 75 inside washer of the idler 17 for feeding. Each is free to move relatively to the other and therefore, both may adjust themselves to different levels of the material. The pressure exerted by the plunger 30 upon the material may be regulated by turning the screw 80 54 to raise or lower the plunger-bar in relation to the feed-bar.

The presser-foot 18 is preferably made in the form of a thin plate curving around the feed foot and the plunger in a half circle, the end lying adjacent to the gauge 14. The presser foot 18 is secured by a screw 60 to a presser-foot lever 61 pivotally mounted on the upper arm at 62. The presser-foot is 85 normally pressed toward the work-plate 13 by a spring 63 located between a socket-bolt 64 set in a bracket 65 on the upper arm 10 and the presser-foot lever 61. The socket-bolt is adjustable in the bracket 65 and is 90 held in place by a lock nut 67. For raising the presser-foot the split collar 37 on the end of the rock-shaft 36 is provided with a lug 68 arranged to act against a screw 70 set in the presser-foot lever 61 so that when the 95 rock-shaft 36 is rocked the lug 68 moves to the left, referring to Figure 1, and throws the upper portion of the plunger-foot lever 61 to the right, thereby raising the presser-foot from the work-table. The timing of 100 this operation and the amount of the raise may be regulated by turning the screw 70 and securing it in adjusted position by a lock-nut 71. If, for any reason, it is desired to raise the presser-foot, either to remove the 105 work or for some other reason, the upper end of the presser-foot lever 61 may be thrown to the left, referring to Figure 1, by the finger of the operator.

Where the machine is to be used for folding parts of rubber shoes I have found it 115 advantageous to provide the operating face of the hammer 19 with a slot 73 running parallel to the line of feed; otherwise the hammer is not changed in any respect.

For the operation of the various parts in folding, if it is material, reference may be made to the said Lautenschlager patent, because the folding of the edge of the material proceeds as there described. The difference 125 in results secured, namely, the imprint of a lineal pattern or design on the material, is accomplished by the novel elements embodying my invention. As the material is fed through the machine wrong side up it is 130

pressed down upon the pinking disk by the plunger and fed while in contact therewith. At the end of the feeding movement the feed-foot and plunger are raised and the 5 presser-foot descends to hold the material while the feed-foot and plunger travel toward the operator to the starting point where they descend, and the plunger again presses the material upon the pinking disk 10 and holds it there while the material is fed.

At the conclusion of the folding operation the design will be found imprinted upon the right side of the material adjacent to the folded edge.

15 Although my machine is designed with particular reference to the imprinting of a lineal design upon rubber parts while being folded, yet it is not to be limited to that particular material since the machine may 20 be used on any material capable of receiving and holding an imprinted design. At the same time, my invention may be embodied in various other forms of construction than that herein shown and described, all within 25 the purview of my invention.

What I claim is:—

1. A folding machine having, in combination, a work-support, fold-turning means, 30 fold-pressing means and rotatable means for impressing a design upon the outer surface of the material being folded.

2. A folding machine having, in combination, a work support, fold-turning means, fold-pressing means and rotatable means for 35 impressing a continuous design upon the outer surface of the material being folded adjacent to the folded edge thereof.

3. In a folding machine, the combination 40 with a work-support, means for turning over the edge to be folded, and means for pressing down said turned over edge, of means for feeding the material; said feeding means having provision for impressing a design upon the outer surface of said material.

45 4. In a folding machine, the combination of a work-support, means for feeding the material, means for turning over the edge to be folded, means for pressing down upon the body-portion said turned over edge and 50 rotatable means for impressing a lineal design upon the outer surface of the material being folded simultaneously with the folding operation.

55 5. In a folding machine, the combination with folding instrumentalities of a rotatable member having a pinking periphery for impressing a design upon the outer surface of the material being folded and means for pressing the material against said rotatable 60 member.

6. In a folding machine, the combination with feeding and folding instrumentalities of a member having a periphery formed for impressing a design, said member being 65 adapted to be rotated by the material as it is

fed through the machine and a plunger for pressing the material against the periphery of said member.

7. In a folding machine, the combination with folding instrumentalities of a rotatable 70 disk having a pinking periphery for impressing a lineal design upon the outer surface of the material being folded and a plunger for pressing the material against the periphery of said disk.

75 8. In a folding machine, the combination with feeding and folding instrumentalities of a rotatable disk having a periphery formed for imprinting a lineal design upon the outer surface of the material being folded 80 adjacent to the folded edge thereof and being adapted to be rotated by the material through the feeding movement thereof and a plunger for pressing the material against the periphery of said disk during said feeding 85 movement.

9. In a folding machine, the combination with feeding and folding instrumentalities of a rotatable member provided with means for imprinting a lineal design on the outer 90 surface of the material being folded and means for pressing said material against said impressing means, said rotatable member being made up of two washers having interposed between them a disk of greater diameter than the washers and having its periphery formed for imprinting a lineal design.

95 10. In a folding machine, the combination of means for feeding the material, means for turning over the edge to be folded, means for 100 pressing down said turned over edge, a rotatable disk having a periphery formed for imprinting a lineal design upon the outer surface of the material being folded adjacent to the folded edge thereof and being adapted 105 to be rotated by the feeding movement of the material and a plunger for pressing the material against the periphery of said disk during the feeding movements.

11. In a folding machine, the combination with folding instrumentalities of a rotatable disk having a pinking periphery for impressing a design upon the outer surface of the material being folded and a plunger for 110 pressing the material against the periphery of said disk, said plunger having a feeding movement while in engagement with the material.

115 12. In a folding machine, the combination with feeding and folding instrumentalities of a member having a periphery formed for impressing a design, said member being adapted to be rotated by the material as it is fed through the machine and a plunger for 120 pressing the material against the periphery of said member during the feeding movement, said plunger being carried by the feeding instrumentalities and moving in unison therewith throughout the feeding movement.

13. In a folding machine, the combination with feeding and folding instrumentalities of a rotatable disk having a periphery for impressing a design upon the outer surface 5 of the material being folded and means for pressing the material against the periphery of said disk, said means being carried by said feeding means and moving therewith during the feeding movement.
14. In a folding machine, the combination of means for turning over the edge to be folded, means for pressing down the turned over edge, means for feeding the material in a step-by-step manner, said feeding 15 means comprising a hollow feed-bar and a feed-foot carried thereby, rotatable means for impressing a design upon the outer surface of the material and means slidably mounted within said hollow feed-bar for 20 holding the material in engagement with said rotatable means during the feeding movement.
15. In a folding machine, the combination of means for turning over the edge to be folded, means for pressing down the turned over edge, means for feeding the material in a step-by-step manner, said feeding means comprising a hollow feed-bar and a feed-foot carried thereby, rotatable means for 25 impressing a design upon the outer surface of the material and a plunger slidably mounted within said hollow feed-bar for holding the material in engagement with said rotatable means during the feeding movement.
16. In a folding machine, the combination of means for turning over the edge to be folded, means for pressing down the turned over edge, means for feeding the material 30 in a step-by-step manner, said feeding means comprising a hollow feed-bar and a feed-foot carried thereby, rotatable means for impressing a design upon the outer surface of the material, a plunger slidably
- mounted in said hollow feed-bar for pressing the material upon said rotatable means, said plunger having a longitudinal movement relative to said feed-bar and resilient means for holding said plunger in a downward position. 45
17. In a folding machine, the combination of means for turning over the edge to be folded, means for pressing down said turned over edge, means for feeding the material in a step-by-step manner, said means comprising a hollow feed-bar and a feed-foot carried by said feed-bar, a rotatable disk for impressing a design upon the outer surface of the material to be folded, a plunger slidably mounted within said hollow feed-bar 50 for pressing the material against said disk and moving in unison with said feed-bar during the feeding movement and resilient means for pressing said plunger downwardly against the material during the feeding movement. 55
18. A folding machine having, in combination, a work-support, fold-turning means, a fold-presser having its pressing surface provided with a slot parallel to the line of feed of the material, and feeding means having provision for impressing a design upon the said material. 60
19. In a folding machine, the combination with folding instrumentalities of a rotatable disk adapted for impressing a design upon the surface of the material being folded and resilient means for holding the material in engagement with said disk. 65
20. In a folding machine, the combination with folding instrumentalities of a rotatable member adapted to impress a design upon the material being folded and a feeding member for feeding the material while in engagement with said rotatable member. 70

In witness whereof, I hereunto set my hand this thirteenth day of August, 1920.

JOHN GLENDON.
